By James L. Morris, attorney.

UNITED STATES PATENT OFFICE.

FREDERICK V. JONES, OF ZYLONITE, MASSACHUSETTS, ASSIGNOR TO THE
UNITED ZYLONITE COMPANY, OF SAME PLACE.

DESIGN FOR A BRUSH OR MIRROR BACK.

SPECIFICATION forming part of Design No. 20,112, dated August 26, 1890.

Application filed July 9, 1890. Serial No. 358,203. Term of patent 7 years.

To all whom it may concern:

Be it known that I, FREDERICK V. JONES, a citizen of the United States, residing at Zylonite, in the county of Berkshire and State 5 of Massachusetts, have invented and produced a new and original Design for Backs for Toilet Articles, of which the following is a specification.

This design has for its object to provide a 10 novel, ornamental, attractive, and variegated back for toilet articles, such as brushes and mirrors; and the leading feature thereof resides in a skeleton frame comprising a central oval or circular shaped band or rib and 15 scrolls connecting such band or rib with the edge of the skeleton frame, the whole having a background of a color distinguished from the color of the skeleton frame.

The design is illustrated by the accompanying drawing, in which the figure is a plan view 20 of the brush or mirror back.

In the drawing, the numeral 1 indicates the skeleton frame extended into an ornamental handle 2, and comprising a central ornamented oval or circular shaped band or rib 4 25 and scrolls 5, terminating at one extremity as leaves 6, and connecting the oval-shaped band or rib 4 with the outer edge or margin 7 of the skeleton frame, the whole being provided with a background 3 of a color distinguished from the color of the skeleton frame. The background may be variegated in dark colors and the skeleton frame may be white.

What I claim is—

The design for a brush or mirror back, substantially as shown and described. 35

In testimony whereof I have affixed my signature in presence of two witnesses.

FREDERICK V. JONES.
